C. E. COLE

FLASHING MOLD

Filed July 19, 1923

Inventor
C. E. Cole.

Attorney

UNITED STATES PATENT OFFICE.

CLIFFORD E. COLE, OF BIRMINGHAM, ALABAMA.

FLASHING MOLD.

Application filed July 19, 1923. Serial No. 652,480.

To all whom it may concern:

Be it known that I, CLIFFORD E. COLE, a citizen of the United States of America, residing at Birmingham, in the county of

5 Jefferson and State of Alabama, have invented certain new and useful Improvements in Flashing Molds, of which the following is a specification.

My invention relates to a mold for forming 10 a lead lip or ring on a flashing plate.

The object of my invention is to perfect an apparatus for the manufacture of the type of flashing forming the subject matter of Letters Patent No. 1,287,235, issued to 15 myself on December 10th, 1918, wherein I show a flashing formed of a galvanized metal plate having a raised flange in the shape of a truncated cone formed therein and provided at its upper edge with suitable grip or

20 lock means which are cast jointed in a lead flange or lip which gives the desired shape and arrangement to the pipe engaging portion of the flashing. In perfecting an apparatus for the molding of this lead flange

25 on the flashing plate, I provide a male die and mold member adapted to fit into and project through the flange on the flashing plate and I hinge a female die or mold member so that it will swing towards and

30 can be clamped so as to press the base of the flange on the flashing plate against the male die, said dies being shaped to provide the necessary annular mold space for the lead ring into which the top edge of the 35 flashing flange projects. The assembled mold is then swung from horizontal to vertical position and the lead ring is poured.

The details of construction of my invention and manner of operation will be better 40 understood by reference to the accompanying drawings which form a part of this specification, and in which:—

Fig. 1 is a side elevation of the assembled mold ready for pouring.

45 Fig. 2 is a front elevation of the mold opened up preparatory for mounting a flashing plate thereon.

Fig. 3 is a longitudinal cross-sectional view showing the mold assembled with the 50 finished flashing in cross-section, the runner being omitted for the sake of clearness.

Fig. 4 is a detail view in elevation of the male die member of the mold.

Similar reference numerals refer to similar parts throughout the drawings.

55 In the preferred embodiment of my invention illustrated, I show my mold apparatus mounted upon a pipe or pivot support 1 overhung in bearings 2 from a work table or suitable support 3. The mold apparatus

60 comprises a base plate 4 having connected thereto clips 5 which clamp it to the pipe 1 and having formed near its free edge an opening 6 which, when in horizontal position, comes over a burner 7 used to maintain the mold at the proper temperature.

65 On the upper side of the base plate 4 I mount the male mold die 8 which has a hollow body surrounding the opening 6 and formed with an upwardly tapering recess or chamber 9 therein. This male die 8 is

70 provided with a marginal base flange 10 merging into a sloping surface 11 which conforms to the inside shape of the upturned flange 12 previously formed on the

75 metal flashing plate 13. This flashing plate is of any suitable material, galvanized metal being generally used. This surface 11 (see Fig. 4) merges into a narrow horizontal ledge 14 which stands slightly below the

80 top edge of the flashing flange 12 when the flashing is assembled on the male die (see Fig. 3). Above the ledge 14 the upper or

85 mold portion 15 of the die is given the peculiar conformation shown, which is that preferred for the inside shape of the lead lip to be cast jointed to the plate flange 12. This lip or neck, it will be observed,

90 is longer on one side than the other, thus causing its axis to stand at the desired inclination to the plane of the plate. The portion 15 terminates in a ledge or shoulder 16 from the center shouldered portion of which rises a screw post 17 having its

95 sides cut away for affording the quick-action clamp and release hereinafter described.

The female die is connected to a pair of hinge arms 18 extending beyond the pivot pipe and there hingedly connected to lugs 19 made fast to the top surface of the base

100 plate. These arms 18 at their free ends are connected by a front cross member 20 which

as shown is formed as an integral part with the arms and they are also cross braced by a bar 21. The frame members 20 and 21 are suitably secured to the neck portion 22 5 on the female die, said portion terminating overhead in a shoulder or flange 23 against which a shoulder on the nut 24 bears, the upper end of the nut rising through and above the flange and having made fast there- 10 on a handle 25. The nut rotates in a cylindrical recess formed in the shoulder 22 and has at opposite ends partial threads 27 which are adapted to co-act with the partial threads on the screw post 17 when the nut 15 is turned to the position shown in Fig. 3. When however the nut is swung 90° in either direction from the position shown in Fig. 3, its threads entirely disengage the threads on the post, leaving the mold die 20 members free to separate. When however the threads are engaged and the handle 25 is moved to the position shown in Fig. 3, the die members are not only engaged but they are positively clamped together. The 25 female die on its internal surface has a shoulder 28 which engages the ledge 16 of the male die and overhangs beyond same the width of the upper edge of the lead lip 29. From the outer edge of this shoulder 28 30 the inner mold surface proper bulges inwardly to thin out the metal in the neck near its center and then flares outwardly and downwardly to form the base portion 30 of the mold which conforms to and is 35 adapted to engage and clamp the plate flange 12 when the mold die members are clamped together. The female die is formed with a pouring gate 31. The base plate 4 is provided with a lifting grip or handle 32. 40 The swinging mold frame members 18 carry a stop lug 33 which will engage the base plate and hold the frame in upright position.

In operation, the base plate 4 is lowered to horizontal position, the female die is 45 swung up into open position, see Fig. 2, a flashing plate 12 is fitted over and pressed down on the male die 8, the female die is then swung down with the handle 25 in the position shown in Fig. 2, which brings a 50 screw post and the nut into assembled position ready for their threads to engage. The arm 25 is then swung around 90°, clamping the female die against the male die and causing the die portions 11 and 30 to clamp 55 firmly between them the plate flange 12, leaving its upper edge projecting into the mold cavity above the ledge 14. The handle 32 is then grasped, the mold is swung into upright position, the lead is poured 60 through the gate 31 and fills the annular cavity in the mold and at the same time cast joints itself to the top of the plate flange 12. The arm 23 is swung back to horizontal 65 position and the female die is raised to vertical position. The operator then with a

chisel removes the runner, and the result is the finished flashing, as shown in cross section in Fig. 3. The operation can be very rapidly performed and the molds are kept at the correct temperature by the burner 6 70 so as to prevent the lead chilling too rapidly.

Though I have described with great particularity the details of the embodiment of the invention herein shown, it is not to be construed that I am limited thereto, as changes in arrangement and substitution of equivalents may be made by those skilled in the art without departing from the invention as defined in the appended claims. 75

Having thus described my invention, what 80 I claim as new and desire to secure by Letters Patent, is:—

1. A mold of the character described, comprising co-acting male and female dies having substantially frusto conical portions 85 adapted and shaped to firmly embrace all but the upper edge of a raised annular flange formed in a flashing plate, said dies providing a mold cavity for the cast jointing of a lead lip about the exposed upper 90 edge of said flange, a gate for pouring the metal to form said lip, and means to clamp the dies in operating position.

2. A mold according to claim 1, in combination with a hinged support on which the 95 assembled mold is adapted to be swung into upright position for pouring the lip metal, and means to heat the mold while in its lowered position.

3. A mold in accordance with claim 1, in 100 which the means to clamp the dies in operating position comprises co-acting screw members having their threads partially removed and adapted to be engaged and released by a partial relative rotation, and co-acting elements on the dies to exclude the molten lip metal from the screw members. 105

4. A mold for casting a lead lip ring on a raised flashing plate flange, which comprises a male die fitting snugly into and projecting through and above the plate flange, a female die adapted to fit over the male die and to snugly embrace the plate flange, said mold dies having walls shaped and spaced to form a lip ring mold cavity into which 110 the upper end of the plate flange projects, a gate giving access to said mold cavity, and means to clamp said dies together with their base portions tightly engaging the base of 115 said plate flange.

5. A mold in accordance with claim 4, in combination with a pivotally mounted supporting plate adapted to swing the assembled mold into upright position with the gate uppermost, and a heater to which the 120 mold is exposed when the support is in lowered position.

6. In a mold of the character described, a base plate hinged to swing vertically and having near its free end a handle and an 125

opening, a hollow male die mounted over co-acting surfaces on the mold dies adapted said opening, a burner disposed below said to receive and snugly clamp between them opening when the plate is in horizontal position, the base portion of the raised annular 10 flange of a flashing plate.

5 said plate and adapted to swing down into assembled position over the male die, means to lock the dies in assembled position, and

In testimony whereof I affix my signature.

CLIFFORD E. COLE.
